UNITED STATES PATENT OFFICE.

JOSEPH A. DAINTY, OF NEWARK, NEW JERSEY.

DETONATING TOY.

No. 927,775.

Specification of Letters Patent.

Patented July 13, 1909.

Application filed October 14, 1908. Serial No. 457,604.

To all whom it may concern:

Be it known that I, JOSEPH A. DAINTY, a citizen of the United States, residing at Newark, in the county of Essex and State of New Jersey, have invented certain new and useful Improvements in Detonating Toys; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in toys; and, the invention has reference, more particularly to a novel detonating toy which is made in the form of a revolving body or element upon which a strip or band of fulminates can be arranged, and provided with means for successively exploding the fulminates when the revolving body or element is moved along the floor, or is otherwise caused to be revolved.

This invention has for its principal object to provide a novel and simply constructed device of the general character hereinafter more fully set forth, which can be readily manipulated, and the several parts of which operate most effectively to successively explode the fulminates which are arranged upon the said revolving body or element.

Other objects of this invention not at this time more particularly mentioned will be clearly evident from the following detailed description.

With the various objects of my present invention in view, the said invention consists, primarily, in the novel detonating toy hereinafter set forth; and, the invention consists, furthermore, in the novel arrangements and combinations of devices and parts, as well as in the details of the construction of the same, all of which will be hereinafter more fully described, and then finally embodied in the clauses of the claims which are appended to and which form an essential part of this specification.

The invention is clearly illustrated in the accompanying drawings, in which:—

Figure 1 is a side elevation of a detonating

toy embodying the principles of this invention, the handle with which the device is provided being shown in portions. Fig. 2 is an edge view of the device, showing the handle broken away; and Fig. 3 is a central vertical section of the parts represented in said figures. Fig. 4 is a transverse vertical section of the revolving body or element, showing the exploding anvils, a means for rolling said body or element, and a means for retaining the strip or band of fulminates upon said revolving body or element.

Similar characters of reference are employed in all of the said figures of the drawings, to indicate corresponding parts.

Referring now to the said drawings, the reference-character 1 indicates the complete detonating toy, the same comprising a suitable handle 2 which is provided at one end with a handle-portion 3 and at its other end with a suitable pintle 4, formed at one end with a head 5 and at its other end with suitable fastening means, as 6. Rotatably arranged upon said pintle 4 is a suitable main body or element, as 7, which is preferably made in the form of a cylindrical disk, being made of wood, or any other desired material. Suitably arranged upon one of the side-faces of said disk is a plate 8, preferably of sheet-metal, said plate being provided with a multiplicity of outwardly extending and preferably pointed members, as 9, formed with the convex marginal edge 10 and the concave marginal edge 11, said edges meeting in a point, substantially as shown. The said plate 8 is also made with a multiplicity of perforated portions or members 12, intermediate of each pair of members 9, said portions or members 12 being bent at right angles to the plane of the faces of said plate 8, said portions or members 12 resting directly upon the cylindrical surface of the main body or element 7, and being secured thereto in any suitable manner, preferably by means of nails or tacks 14, substantially in the manner illustrated in Figs. 2 and 4 of the drawings. These right-angled members or portions 12, as well as the heads of the nails or tacks 14 form suitable anvils for the exploding thereon of the fulminates, in the manner to be presently more fully described. From an inspection of the several figures of the drawings, it will also be seen, that each member 9 has

forced out of its body, so as to extend at a right angle from said body, a prong, lug, or element 13, said prongs or lugs being located slightly above the cylindrical surface of the 5 main body or element 9, so as to provide suitable receiving spaces 15, substantially as shown in the several figures.

Secured to the handle 2 at a suitable point, and preferably upon a block or enlargement 10 16 which extends from the side of the handle, is an arm or member 17, the same being made from a suitable spring-like material, and having at its one end a laterally projecting finger or extension 18 which rides upon and over 15 the previously mentioned pointed members or element 9, so that the spring-like action of the arm 17 will cause the said projecting finger or extension 18 to be forcibly brought down upon the anvils formed by the portions 20 or members 12 and the heads of the nails or tacks 14, between each pair of adjacent members 9, as will be clearly understood from an inspection of the several figures of the drawings.

25 The strip or tape of fulminates is indicated by the reference-character 19, and the fulminates or explosive matter which are spaced at desired equal distances from each other, are indicated by the reference character 20. To 30 attach a strip or band in its position about the peripheral surface of the main body or element 7, it is arranged about the said surface in the manner illustrated in Fig. 1 of the drawings, with portions of the said strip or 35 band arranged directly beneath the laterally extending lugs or prongs 13, which securely hold or retain the said strip or band in place. The arrangement of the said strip or band upon the body or element 7, in the manner 40 above stated, is such that the fulminates are located directly over and upon the anvils formed by the said laterally extending members or elements 12.

Having arranged the strip or band of fulminates upon the said main body or element 45 7 of the toy, by taking hold of the handle-portion 3 of the handle 2, the rolling body or element 7 is made to revolve by placing the pointed members 9 upon the floor or ground 50 and by pushing upon the handle, in the direction of the arrow *x* in Fig. 4, causing the body 7 to revolve in the direction of the arrow *y*. The result will be that the laterally projecting finger or extension 18 is rapidly vibrated, 55 and every time that it leaves the points of the members 9, it is forcibly brought in engagement with a fulminate disposed upon the anvils in the manner herein-above stated.

As has been stated, each pointed member 60 or element 9 is made with the concave marginal edge-portions 11, so that the laterally extending finger or extension 18 in its downward movement will immediately drop upon the anvil without scraping against the said 65 edge-portions of the members or elements 9,

as will be clearly evident. Thus, it will be clearly evident, that the fulminates are readily exploded in rapid succession, providing a simply and cheaply made toy which gives great pleasure and amusement.

I am aware that some changes may be made in the arrangements and combinations of the various devices and parts, as well as in the details of the construction of the same, without departing from the scope of my present invention as defined in the appended claims. Hence I do not limit my invention to the exact arrangements and combinations of the various devices and parts as set forth in the foregoing specification, nor do I confine myself to the exact details of the construction of the said parts, as illustrated in the accompanying drawings.

I claim:

1. A detonating toy comprising a rotatable main element about the peripheral surface of which a strip of fulminates is adapted to be arranged, means for rolling the said main element, and means for producing an explosion of the fulminates during the rolling 90 of said main element.

2. A detonating toy comprising a handle, a main element rotatably connected with said handle, means for securing a strip of fulminates upon said main element, and means 95 for producing an explosion of the fulminates during the rolling of said main element.

3. A detonating toy comprising a handle, a main element rotatably connected with said handle, means for securing a strip of fulminates upon said main element, and a vibratory spring-arm provided with means for 100 producing an explosion of the fulminates during the rolling of said main element.

4. A detonating toy comprising a handle, 105 a main element rotatably connected with said handle, means for securing a strip of fulminates upon said main element, a multiplicity of anvils upon which the fulminates of said strip are disposed, and means adapted 110 to be brought in engagement with each fulminate for producing the explosion of the same during the rolling of said main element.

5. A detonating toy comprising a handle, 115 a main element rotatably connected with said handle, means for securing a strip of fulminates upon said main element, a multiplicity of anvils upon which the fulminates of said strip are disposed, and a vibratory spring-arm provided with means for producing 120 an explosion of the fulminates during the rolling of said main element.

6. A detonating toy comprising a rotatable main element about the peripheral surface of which a strip of fulminates is adapted 125 to be arranged, pointed members extending from the said main element adapted to be brought in rolling engagement with the floor, or the like, means for producing the rolling of said main element and the pointed 130

members, and means adapted to be brought in engagement with and to be actuated by said pointed members for producing an explosion of the fulminates during the rolling 5 of the main element.

7. A detonating toy comprising a handle, a main element rotatably connected with said handle, means for securing a strip of fulminates upon said main element, pointed 10 members extending from said main element adapted to be brought in rolling engagement with a floor, or the like, and means adapted to be brought in engagement with and to be actuated by said pointed members for producing 15 an explosion of the fulminates during the rolling of the main element.

8. A detonating toy comprising a handle, a main element rotatably connected with said handle, means for securing a strip of fulminates upon said main element, pointed 20 members extending from said main element adapted to be brought in rolling engagement with a floor, or the like, a vibratory spring provided with means adapted to be brought 25 in engagement with and to be actuated by said pointed members for producing an explosion of the fulminates during the rolling of the main element.

9. A detonating toy comprising a handle, 30 a main element rotatably connected with said handle, means for securing a strip of fulminates upon said main element, pointed members extending from said main element adapted to be brought in rolling engagement 35 with a floor, or the like, a multiplicity of anvils upon which the fulminates of the strip are disposed, and means adapted to be brought in engagement with and to be actuated by said pointed members for producing 40 an explosion of the fulminates during the rolling of the main element.

10. A detonating toy comprising a handle, a main element rotatably connected with said handle, means for securing a strip of fulminates upon said main element, pointed 45 members extending from said main element adapted to be brought in rolling engagement with a floor, or the like, a multiplicity of anvils upon which the fulminates of the strip are disposed, and a vibratory spring provided 50 with means adapted to be brought in engagement with and to be actuated by said pointed members for producing an explosion of the fulminates during the rolling of the main element.

11. A detonating toy comprising a handle, a pivot-pin upon said handle, a main element rotatably arranged upon said pivot-pin, a metal plate upon one side of said main element, said plate being formed with members 60 projecting at right angles from the side of said plate, pointed members forming an integral portion of and extending from said plate, said pointed members being adapted to be brought in rolling engagement with a floor, or the like, retaining prongs extending 65 from the sides of said pointed members being adapted to be brought in engagement with and to be actuated by said pointed members for producing an explosion of the fulminates during the rolling of the main element.

or the like, means for securing a strip of fulminates upon said main element and over said right - angled members, and means adapted to be brought in engagement with and to be actuated by said pointed members 70 for producing an explosion of the fulminates during the rolling of the main element.

12. A detonating toy comprising a handle, a pivot-pin upon said handle, a main element rotatably arranged upon said pivot-pin, a 75 metal plate upon one side of said main element, said plate being formed with members projecting at right angles from the side of said plate, pointed members forming an integral portion of and extending from said 80 plate, said pointed members being adapted to be brought in rolling engagement with a floor, or the like, means for securing a strip of fulminates upon said main element and over said right-angled members, a vibratory 85 spring secured at one end to said handle, and a laterally extending hammer-like extension at the other end-portion of said spring adapted to be brought in engagement with and to be actuated by said pointed members for 90 producing an explosion of the fulminates during the rolling of the main element.

13. A detonating toy comprising a handle, a pivot-pin upon said handle, a main element rotatably arranged upon said pivot-pin, a 95 metal plate upon one side of said main element, said plate being formed with members projecting at right angles from the side of said plate, pointed members forming an integral portion of and extending from said 100 plate, said pointed members being adapted to be brought in rolling engagement with a floor, or the like, retaining prongs extending from the sides of said pointed members for 105 securing a strip of fulminates between said prongs and the said right-angled members, and means adapted to be brought in engagement with and to be actuated by said pointed members for producing an explosion of 110 the fulminates during the rolling of the main element.

14. A detonating toy comprising a handle, a pivot-pin upon said handle, a main element rotatably arranged upon said pivot-pin, a 115 metal plate upon one side of said main element, said plate being formed with members projecting at right angles from the side of said plate, pointed members forming an integral portion of and extending from said 120 plate, said pointed members being adapted to be brought in rolling engagement with a floor, or the like, retaining prongs extending from the sides of said pointed members for securing a strip of fulminates between said 125 prongs and the said right-angled members, a vibratory spring secured at one end to said handle, and a laterally extending hammer-like extension at the other end-portion of said spring adapted to be brought in engagement with and to be actuated by said pointed 130 members.

members for producing an explosion of the fulminates during the rolling of the main element.

15. A detonating toy comprising a handle, 5 a pivot-pin upon said handle, a main cylindrical element rotatably arranged upon said pivot-pin, a metal-plate upon one side of said main element, said plate being formed with perforated members projecting at right angles from the side of said plate, said right-angled members extending over the cylindrical surface of said main element, nails extending through said right-angled members for securing them to said cylindrical surface, 60 10 pointed members forming an integral portion of and extending from said plate, said pointed members being adapted to be brought in rolling engagement with a floor, or the like, 65 15 means for securing a strip of fulminates upon said main element and over said right-angled members, and means adapted to be brought in engagement with and to be actuated by said pointed members for producing an explosion of the fulminates during the 70 20 25 rolling of the main element.

16. A detonating toy comprising a handle, a pivot-pin upon said handle, a main cylindrical element rotatably arranged upon said pivot-pin, a metal-plate upon one side of said 30 main element, said plate being formed with perforated members projecting at right angles from the side of said plate, said right-angled members extending over the cylindrical surface of said main element, nails extending 35 through said right-angled members for securing them to said cylindrical surface, pointed members forming an integral portion of and extending from said plate, said pointed members being adapted to be brought in rolling 40 engagement with a floor, or the like, means for securing a strip of fulminates upon said main element and over said right-angled members, a vibratory spring secured at one 45 end to said handle, and a laterally extending hammer-like extension at the other end-portion of said spring adapted to be brought in engagement with and to be actuated by said pointed members for producing an explosion of the fulminates during the rolling of the 50 main element.

17. A detonating toy comprising a handle, a pivot-pin upon said handle, a main cylindrical element rotatably arranged upon said pivot-pin, a metal-plate upon one side of said 55 main element, said plate being formed with perforated members projecting at right angles

from the side of said plate, said right-angled members extending over the cylindrical surface of said main element, nails extending through said right-angled members for securing them to said cylindrical surface, pointed members forming an integral portion of and extending from said plate, said pointed members being adapted to be brought in rolling engagement with a floor, or the like, 60 65 retaining prongs extending from the sides of said pointed members for securing a strip of fulminates between said prongs and the said right-angled members, and means adapted to be brought in engagement with and to be 70 actuated by said pointed members for producing an explosion of the fulminates during the rolling of the main element.

18. A detonating toy comprising a handle, a pivot-pin upon said handle, a main cylindrical element rotatably arranged upon said pivot-pin, a metal-plate upon one side of said main element, said plate being formed with perforated members projecting at right angles from the side of said plate, said right-angled members extending over the cylindrical surface of said main element, nails extending through said right-angled members for securing them to said cylindrical surface, pointed members forming an integral portion of and extending from said plate, said pointed members being adapted to be brought in rolling engagement with a floor, or the like, 75 80 retaining prongs extending from the sides of said pointed members for securing a strip of fulminates between said prongs and the said right-angled members, and means adapted to be brought in engagement with and to be actuated by said pointed members for producing an explosion of the fulminates 85 90 95 during the rolling of the main element, a vibratory spring secured at one end to said handle, and a laterally extending hammer-like extension at the other end-portion of said spring adapted to be brought in engagement with and to be actuated by said pointed members for producing an explosion of the fulminates 100 during the rolling of the main element.

In testimony, that I claim the invention 105 set forth above I have hereunto set my hand this 13th day of October, 1908.

JOSEPH A. DAINTY.
